UNITED STATES PATENT OFFICE.

DOMINIC M. WALL, OF EAST PROVIDENCE, RHODE ISLAND, ASSIGNOR TO F. T. PEARCE COMPANY, OF PROVIDENCE, RHODE ISLAND, A CORPORATION OF RHODE ISLAND.

DESIGN FOR A PENCIL-CASING.

47,311.

Specification for Design.

Patented May 4, 1915.

Application filed January 18, 1915. Serial No. 2,989. Term of patent 7 years.

To all whom it may concern:

Be it known that I, DOMINIC M. WALL, a citizen of the United States, residing in the town of East Providence, county of Providence, State of Rhode Island, have invented a new, original, and ornamental Design for a Pencil-Casing, of which the following is a specification, reference being had to the accompanying drawing, forming part thereof.

The figure is a side elevation of the pencil casing illustrating my new design.

I claim:

The ornamental design for a pencil casing, as shown.

DOMINIC M. WALL.

Witnesses:

HOWARD E. BARLOW,
A. F. MACREADY.
